United States Patent Office.

GERMAN J. MATSON, OF ALMA, MICHIGAN, ASSIGNOR TO HIMSELF AND SAMUEL F. JUDD, OF SAME PLACE.

Letters Patent No. 95,247, dated September 28, 1869.

IMPROVED WASHING-MACHINE.

The Schedule referred to in these Letters Patent and making part of the same.

To whom it may concern:

Be it known that I, GERMAN J. MATSON, of Alma, in the county of Gratiot, and State of Michigan, have invented a new and useful Improvement in Washing-Machine; and I do declare that the following is a true and accurate description thereof, reference being had to the accompanying drawings, and to the letters of reference marked thereon, and being a part of this specification, in which—

Figure 1 is a perspective view of my invention.

Figure 2 is a vertical longitudinal section of the same.

Like letters indicate like parts in each figure.

The nature of this invention relates to an improvement in the construction of machines for washing textile fabrics; and consists in a new, novel, and peculiar arrangement of its parts which rub the clothes, and in the devices for operating the same, as hereinafter more fully shown and set forth.

A, in the drawings, represents a water-tight rectangular box, having an inclined bottom, and is supported by proper legs, B.

C are inclined ribs, one of which is secured to each side of the interior of the box, which serve as guides to the lower rub-board D, which is grooved on its sides to receive said ribs.

E is a similar rub-board, working between and guided by the slides F, which are inclined at the same angle as the ribs C.

The slides F are not secured to the sides of the box, but are rigidly attached to the lower ends of a gate, G, which slides freely in vertical grooves in the inner sides of the box, into which its inner legs g are halved. The outer legs of the gate are connected together at the bottom of the box, by the bar H, to the bottom of which is secured a downward-projecting headed bolt, h.

I is a single-leaf spring, one end of which is rigidly secured to the cross-bar between the rear legs of the machine, while the other engages with the bolt h and exerts a downward pressure thereon, drawing down the gate and the upper rub-board E, its tension being regulated by a thumb-screw, J, passing through the spring near its centre, and engaging with a nut in the transverse bar K, in the frame-work under the box.

L is a lever or treadle, fulcrumed to the front trans-

verse round of the legs, and operating to raise the gate G and the rub-board E, and relieving the clothes under it from pressure to any desired extent, as in washing light fabrics.

The legs of the gate are connected to the bar H, by screws M, which readily allow the same to be taken apart, and the rub-board to be removed from the box.

N are brackets, projecting from the front corners of the box, and into which is journalled the tumbling-shaft O, which is operated by the hand-lever P.

Q are double-armed levers, secured to the shaft O, and which give a reciprocating motion to the rub-boards D and E, through the connecting-rods R, the lower pair of which operate through appropriate slots cut in the front side of the box for that purpose.

S is an orifice, in the lower and rear part of the box, for discharging its liquid contents, when necessary.

The rub-boards are serrated, as shown in fig. 2, and may be longitudinally waved or corrugated, to increase their efficiency.

To operate this device, the clothes being in the front part of the box, which is partly filled with hot suds, raise the upper rub-board by depressing the treadle L, and introduce the article to be washed, release the treadle, and vibrate the lever P, which will cause the rub-boards to reciprocate in opposite directions, pressing and rubbing the article between them, which, after a few motions, will be delivered clean in the rear end of the box.

By drawing off the water after washing, and again passing the clothes between the rub-boards, the water will readily be squeezed out of them.

What I claim as my invention, and desire to secure by Letters Patent, is—

The combination and arrangement of the gate G, the slides F, the spring I, the thumb-screw J, the treadle L, the ribs C, the rub-boards D and E, the connecting-rods R, the levers Q, the shaft O, the lever P, and the brackets N, in connection with the box A, provided with a sloping bottom and an outlet, S, when constructed and operating as aforesaid.

GERMAN J. MATSON.
